J. F. GLOVER.

TUG ADJUSTER,

APPLICATION FILED JULY 12, 1920.

1,369,650.

Patented Feb. 22, 1921.

UNITED STATES PATENT OFFICE.

JOHN FRANKLIN GLOVER, OF TROY, TENNESSEE.

TUG-ADJUSTER.

1,369,650.

Specification of Letters Patent. Patented Feb. 22, 1921.

Application filed July 12, 1920. Serial No. 395,634.

To all whom it may concern:

Be it known that I, JOHN FRANKLIN GLOVER, a citizen of the United States, and a resident of Troy, in the county of Obion and State of Tennessee, have invented certain new and useful Improvements in Tug-Adjusters; and I do hereby declare the following to be a full, clear, and exact description of the invention, such as will enable others skilled in the art to which it appertains to make and use the same.

The present invention relates to improvements in tug adjusters, and has for an object to provide an improved device associated with the hame of a horse collar for adjustably connecting the traces thereto, to accommodate the traces to different animals, and to shift the line of draft to meet varying conditions.

Another object of the invention is to provide an improved tug adjuster which will admit of making the required changes in a minimum of time and with but a small degree of effort.

A further object of the invention resides in providing a simple and inexpensive adjustment for hames which may be applied to standard forms of hames without altering the construction thereof, and which will form a durable and efficient device permitting of the adjustment of the traces while locking the same in position, so that it may not accidentally become loose.

The invention will be more fully understood after reference to the accompanying drawings, in which like parts are indicated by similar reference symbols throughout the several views, and in which:

Figure 1 is a plan view of a hame having an improved tug adjuster applied thereto which is constructed according to my invention.

Fig. 2 is an enlarged view, with parts shown in section, of the improved tug adjuster illustrated as in an initial position.

Fig. 3 is a similar view showing the parts in the final position; and

Fig. 4 is a longitudinal sectional view through the same.

Referring more particularly to the drawings, 1 designates one of the hames which is usually constructed of wood, and is secured to the horse collar in a manner which is well known in this art.

According to the invention I provide a plate 2 preferably of metal, although the

same may be of other appropriate material, it being secured by suitable fastenings, as for instance the rivets 3, to the hame 1 at a proper intermediate point thereon. The part 3 is provided with a number of spaced apart studs 4, shown in the embodiment illustrated in the drawings to be six in number, although more or less of these studs may be used to meet various conditions and requirements.

The studs 4 are preferably rectangular in cross section, and have heads 5 also of a substantially similar form, although larger than the bodies of the studs so that the heads may project beyond the edges thereof.

The trace hook 6 is furnished with a shank 7 having a slot near its rear end embodying a relatively large rectangular portion 8 communicating with a smaller rectangular portion 9, communicating therewith at its rear edge. The two portions 8 and 9 of the slot form substantially a keyhole in which to receive the head and shank of the stud to which it is applied. For instance, as shown in Fig. 2, the larger portion 8 is initially fitted over the head 5 of one of the studs, and the device is thereafter moved longitudinally, as indicated in Fig. 3, to a final position where the portion 9 of the slot engages closely about the shank 7 of the stud. The portion 9 of the slot is made to agree substantially with the dimensions of the shank of each stud 4, so that when in the final position shown in Fig. 3 the head 5 of the stud will prevent the shank 7 of the trace hook from being lifted off the stud to which it may have been applied. This shank 7 of the stud is also provided with lateral grooves 10 and 11 in order to receive the adjacent side edges of the two heads 5 of the studs, which lie at opposite sides of the particular stud upon which the device is placed.

The extremity of the shank 7 is also provided with a pair of lugs 12 and 13 which project beyond the sides of the shank and are adapted to engage the body portions of the adjacent studs, as indicated in Fig. 3, so as to limit the forward movement of the trace hook. These lugs 12 and 13 acting against the stud posts 4 also strengthen the device and prevent possible canting of the hook.

Mounted upon the shank 7 is an auxiliary hook 14, which is carried by a shank 15, pivoted on the shank 7 at the point 16, and

adapted to swing in an edgewise direction and in a plane substantially parallel with the first mentioned shank 7.

The hooks 6 and 14 are adapted to aline 5 or come into registry when the shank 15 is moved in a left hand or counter-clockwise direction from the position shown in Fig. 2 to that shown in Fig. 3. In this position the hooks 6 and 14 together receive the trace 10 connection which automatically acts to hold the shank 15 and hook 14 from swinging about the pivot point 16. The rear edge of the shank 15 is rounded, as indicated at 17, on the arc of a circle struck from the central 15 pivot 16 so as to ease the passage of the shank 15 beneath the overhanging head 5 of the stud.

To facilitate the operation, the forward edges of the heads 5, and also, if desirable, 20 the front faces of the studs, may be rounded as indicated at 18 to correspond substantially to the curvature 17 of the rear edge of the shank 15. The shank moves at its rear edge beneath the forward overhanging edge 25 of the head 5 and acts to lock the shank 7 in place thereon. The engagement of the traces in the hooks 6 and 14 is probably all that will be required to prevent the possible disengagement of the shank 15 from the head 30 5 of the stud; but in some instances it may be necessary or desirable to employ some such spring catch as is indicated. This catch embodies a reciprocating pin 19 mounted in guides 20, carried by the shank 35 15. At its forward end the pin 19 is turned upwardly to provide a handle 21 by which the same may be drawn forwardly. A coil spring 22 is wound about the pin 19 between the guides 20, and is secured at one 40 end to said pin so that it may act normally to cause the pin to be projected rearwardly and into a catch 23 provided in the heads 5 of the studs to receive the same.

In operation the shank 7 is first applied 45 by fitting the enlarged portion 8 of the slot over one of the heads 5 of a stud, and thereafter the shank is drawn forwardly to cause the rear portion 9 of this slot to engage the stud. The hook 14 together with its shank 50 15 is then rotated about the pivoted point 16, causing the rear curved edge to enter beneath the head 5. The arrangement may be such that the locking pin will automatically seat within the notch 23. The traces are 55 connected to the hooks 6 and 14 and the device is in readiness for operation.

Should at any time it become necessary to change the adjustment first made, it will prove but a simple operation to disengage 60 the traces from the hooks 6 to 14, and, if employed, the spring latch 19 from the notch 23, after which a hook 14 and shank 15 may be rotated away from the head 5, the innermost shank 7 being then moved 65 rearwardly to bring the larger portion 8 of

the slot in register with the head 5, at which time the shank 7 may be lifted off the stud. A new stud is then selected to meet the requirements of the particular animal of the draft, and a larger portion 8 of the slot is 70 placed upon this newly selected stud, and the processes as previously described are repeated in order to secure the parts in a position of final adjustment.

It will be obvious that various modifications might be made in the herein described apparatus, and in the construction, combination and arrangement of parts which could be used without departing from the spirit of my invention. 75

Having thus described my invention what I claim and desire to secure by Letters Patent of the United States is:—

1. An improved tug adjuster comprising 80 in combination with a hame, a plate adapted to be secured to the hame and having a series of spaced apart and headed studs thereon, a trace hook having a shank provided with a slot near its rear end composed of an enlarged portion adapted to fit over 90 the heads of the studs, and a smaller portion communicating with the larger portion and adapted to embrace the body portions of the studs, an auxiliary hook adapted to register with the first-mentioned hook 95 whereby both hooks may receive traces, said auxiliary hook having a shank pivoted on said first-mentioned shank, the rear end of the auxiliary hook shank adapted to swing beneath the head of the stud occupied by 100 said slot when the auxiliary hook is swung into registry with the trace hook, and yieldable interlocking means arranged between said stud and the shank of the auxiliary hook for preventing the latter from swinging, substantially as described. 105

2. An improved tug adjuster comprising 110 in combination with a hame, a plate adapted to be secured to the hame and having a series of spaced apart and headed studs thereon, a trace hook having a shank provided with a slot near its rear end for interlocking with said studs, an auxiliary hook adapted to register with the trace hook whereby both hooks may simultaneously receive the traces, said auxiliary hook having a shank pivoted to the shank of the trace hook, the rear end of said auxiliary shank adapted to swing beneath the head of the stud occupying said slot, said studs having 115 notches therein, and a spring-pressed plunger carried by the auxiliary hook shank for engaging the notches in said studs, substantially as described.

3. An improved tug adjuster comprising 120 in combination with a hame a plate adapted to be secured to the hame and having a series of spaced apart and headed studs thereon, a trace hook having a shank provided with a slot near its rear end composed of an 125

enlarged portion adapted to fit over the heads of the studs, and a smaller portion communicating with the larger portion and adapted to embrace the body portions of the 5 studs, said shank having lateral grooves in its edges to receive the heads of adjacent studs, lugs projecting laterally from the rear end of said shank and adapted to engage against adjacent studs, an auxiliary 10 hook having a shank pivoted on said first

mentioned shank, such shank having a rear curved edge, the forward edges of the studs being curved to correspond to such curved edge, such curved edge adapted to engage beneath the heads of the studs, and locking 15 means on the last mentioned shank adapted to coöperate with the selected stud, substantially as described.

JOHN FRANKLIN GLOVER.
